UNITED STATES PATENT OFFICE.

ARTHUR G. SHERMAN, OF DETROIT, MICHIGAN.

BOTTLE-STOPPER.

1,375,471.

Specification of Letters Patent. Patented Apr. 19, 1921.

Application filed October 17, 1919. Serial No. 331,460.

To all whom it may concern:

Be it known that I, ARTHUR G. SHERMAN, a citizen of the United States, residing at Detroit, in the county of Wayne and State of Michigan, have invented a new and useful 5 Bottle-Stopper, of which the following is a specification.

This invention relates to bottle stoppers, and more particularly to stoppers for bottles 10 containing vaccine serums or other medical preparations designed to be administered hypodermically by means of a needle.

It is the object of the invention to provide a bottle stopper adapted to be inserted permanently 15 in the mouth of a bottle after the latter has been filled, said stopper being formed either wholly or in part of an elastic material such as soft rubber which may readily be pierced by a hypodermic needle 20 to permit withdrawal of the contents of the bottle, and which will leave no opening when the needle is withdrawn.

To so form such a stopper that it will wedge very firmly in the neck of a bottle, 25 and consequently resist the tendency to shift as the needle is thrust through it or withdrawn, is a further object of the invention.

In attaining these and various other objects the invention contemplates the construction 30 described in the following specification and illustrated in the accompanying drawing, wherein,

Figure 1 is a view in side elevation of a bottle to which the improved stopper is applied.

Fig. 2 is an axial sectional view of the same, taken on line 2—2 of Fig. 1.

Fig. 3 is a sectional view showing the shape of the stopper prior to insertion of the 40 same in the bottle.

Figs. 4 and 5 are respectively a side and top view of the stopper.

In these views the reference character 1 designates a bottle, 2 the neck thereof, and 45 3 a stopper insertible in the mouth of said bottle. Said stopper is of frusto-conical shape and formed of medium hard rubber or like material, capable of being subjected to a considerable degree of compression upon insertion 50 in the neck of the bottle. The smaller or top end of said stopper is provided with a cap portion 4 of soft rubber or like freely yieldable material secured to the main body of the stopper by vulcanizing, cementing, 55 or in any other suitable manner. A recess 5 is extended centrally of the stopper, from

the larger end thereof, to said cap portion, said recess having a taper corresponding to that of the exterior surface of the stopper. When the stopper has been forced into the 60 neck 2, as shown in Fig. 3, the resulting compression of the elastic material reduces both the outer face of the stopper and the recess 5 to cylindrical form. The invention is completed by a pad of absorbent material 65 6 surmounting the cap portion 4 and secured thereto, and the metal cap 7 flanged to embrace the mouth portion of the bottle, and having the clamping ring 8 and member 9 for applying clamping pressure to said ring. 70

The advantage of the described construction lies in the fact that the contents of the bottle 1 may be withdrawn through a hypodermic needle inserted through the relatively soft cap portion 4 of the stopper and 75 through the recess 5 without necessity for removing the stopper from the neck of the bottle. The slight opening formed in said cap portion by piercing the same with the needle is immediately closed when the needle 80 is withdrawn, owing to the elasticity of the material forming said portion, so that the possibility of the contents of the bottle being contaminated by dust or dirt is practically eliminated. By forming the main body portion of the stopper of rubber of only medium softness and providing a central passage therethrough extending to the relatively soft cap portion 4, a firm anchorage for said portion 4 is assured, so that it may undergo 85 no displacement, either into or out of the bottle. The recess 5 gives passage to the hypodermic needle after the same has pierced the portion 4 and furthermore decreases somewhat the resistance offered by the stopper to the compression which it must undergo 90 as it is thrust into the neck of the bottle. The frusto-conical shape of the stopper is of importance, since it insures a definite amount of compression being placed upon 100 the stopper as it is inserted to its position of use, and this amount may be predetermined to insure against longitudinal shifting of the stopper.

The pad 6 may be antiseptically treated 105 so that contact of the needle therewith, while being thrust into the bottle, will have a germicidal effect. The cap 7 forms a final seal, and a protection for the stopper when the bottle is not in use.

What I claim is:

1. The combination with a bottle for re-

ceiving hypodermic solutions, said bottle having a neck portion, of a stopper inserted in said neck portion, formed of elastic material and having a central opening extending therethrough for a major portion of its length, and having integral therewith a portion of relatively soft elastic material subjected to compression through confinement in the bottle neck and normally closing said opening.

2. The combination with a bottle for receiving hypodermic solutions, said bottle having a cylindrical neck portion, of a normally frusto-conical bottle stopper inserted in said neck portion, with its larger end innermost, and compressed to cylindrical form by such insertion, the outer end of said stopper having a cap portion of softer elastic material, and an opening being extended centrally of the stopper from its inner end to said cap portion, said opening conforming to the frusto-conical shape of the stopper prior to insertion in the bottle.

3. The combination with a bottle for re-

ceiving hypodermic solutions, said bottle having a neck portion, of a stopper inserted within said neck portion and comprising an elastic body portion having a central passage therethrough, and a cap portion formed of relatively soft elastic material directly secured to said body portion and closing said passage, a compression of both of said elastic portions being effected by confinement of the stopper in the neck of the bottle.

4. The combination with a bottle for receiving a hypodermic solution, said bottle having a neck portion, of a stopper engaged in said neck portion and forming a permanent closure for the bottle, said stopper having a central passage, and a puncturable self-healing cap member formed of elastic material directly secured to one end of the stopper and subjected to compression by engagement of the stopper in the bottle neck.

In testimony whereof I sign this specification.

ARTHUR G. SHERMAN.
